UNITED STATES PATENT OFFICE.

CHARLES BURGHER, OF BOSTON, MASSACHUSETTS, ASSIGNOR TO THE AUTOMATIC FIRE ALARM AND EXTINGUISHER COMPANY, (LIMITED,) OF NEW YORK, N. Y.

FIRE-ALARM TELEGRAPH.

SPECIFICATION forming part of Letters Patent No. 371,876, dated October 18, 1887.

Application filed June 12, 1886. Serial No. 204,919. (No model.)

To all whom it may concern:

Be it known that I, CHARLES BURGHER, of Boston, in the county of Suffolk and State of Massachusetts, have invented certain new and useful Improvements in Fire-Alarm Telegraphs, of which the following is a full, clear, and exact description, reference being had to the accompanying drawings, forming part of this specification.

10 My invention relates to the class of electric signaling and fire-alarm telegraph systems in which a central station is in constant electric communication with one or more local points for the purpose of receiving and recording 15 signals or fire-alarms in a manner well known.

The principal object of my invention is to provide a more perfect system of fire-alarm telegraphy, whereby the system at times automatically adapts itself to the defective conditions which are continually occurring therein from accident or design, and whereby the system is always maintained in operative condition, and a signal or alarm circuit is constantly established under the various conditions hereinafter set forth.

25 To the above purposes my invention consists in the various novel combinations and sub-combinations of certain features, as herein-after fully described and claimed.

30 In the accompanying drawings, Figure 1 represents a diagrammatic view of my invention, showing the arrangements, constructions, and disposition of the circuits and their contained apparatus, both at the central station and a local point.

35 Fig. 2 represents a front sectional view taken on line 2 2, Fig. 3, of the well-known form of the Watkins signal-box with the modifications and as used in my invention, as hereinafter set out. Fig. 3 represents a 40 side sectional view of the signal-box, taken on line 3 3, Fig. 2. Fig. 4 represents an under side sectional view of the signal-box, taken on line 4 4, Fig. 2. Fig. 5 represents a perspective view of a portion of the signal-box as 45 illustrated in Figs. 2, 3, and 4, showing the signal-transmitting wheels and their co-operating contact-fingers and the switch springs lying beneath. Fig. 6 represents a front sectional view taken on line 6 6, Fig. 7, of my 50 circuit-changing mechanism with the circuit-

connections and as used in my system, as hereinafter set forth.

My circuit-changer is not herein claimed as of itself, for it forms the subject-matter of another application of mine for a patent, and is here merely claimed in connection with the 55 signaling system hereinafter described.

Fig. 7 represents an under side sectional view of my circuit-changer, taken on line 7 7, Fig. 6. Fig. 8 represents a side sectional view 60 of my circuit-changer, taken on line 8 8, Fig. 6. Fig. 9 represents a perspective view of a portion of my circuit-changer as illustrated in Figs. 1, 6, 7, and 8, showing my signal-transmitting wheel and the circuit-changing wheels, 65 with their co-operating contact-fingers and the circuit-connections, as hereinafter fully set out. Fig. 10 represents an under side view of a vibratory thermostat with a portion of the vibrating arm broken away. Fig. 11 represents a sectional view of Fig. 10 on line 11 70 in said figure. Fig. 12 represents a top plan view of an ordinary switch-board mechanism as used in my system, showing the circuit-connections. Fig. 13 represents a side 75 elevation of Fig. 12. Fig. 14 is a diagrammatic view of the normally-closed metallic circuit, and Fig. 15 is a similar view of the re-established circuit after the thermostat has switched the circuit and the circuit-changer 80 has shifted its parts.

In the said drawings like numbers and letters designate corresponding parts throughout.

Referring to the drawings, in Figs. 1, 2, 85 3, 4, and 5, M designates the signaling-box for transmitting electrically-predetermined number-signals, and is of the ordinary form of the Watkins automatic fire-alarm signal-box, with the exception of my modifications 90 in arranging the circuits traversing the electro-magnet and slight changes in the circuit-connections, hereinafter alluded to. This signal-box consists of a base-board upon which is mounted the signal-transmitting apparatus 95 and the protective casing surrounding the same. This apparatus is operated by an ordinary spring-actuated clock-work, U, whose main arbor U' has keyed thereon and revolving therewith the transmitting-wheels V', V², 100

V^3 , V^4 , V^5 , and T , and the check-disk W , which latter is provided with the peripheral notch W' . The wheels V' V^2 V^3 V^4 V^5 are uniform and have similarly disposed upon 5 their peripheries the circuit closing and opening cogs V , respectively arranged side by side and in alignment; also, upon their peripheries are fixed the circuit closing and opening teeth X , which vary in number for each 10 wheel. The wheel T is provided with cogs T' , similar in number and arrangement to cogs V on the other wheels. The block Q , of insulating material, is fastened upon the clock-work frame to one side of the transmitting-wheels, and upon its under face are set by 15 means of screws v the contact-fingers $v' v^2 v^3 v^4 v^5$ and $t t'$, which are flat metallic strips arranged side by side, out of contact, and with their free ends disposed beneath the wheels and 20 disk, mounted on the main arbor and within striking distance of the cogs and teeth thereon when the arbor is rotated.

Directly below block Q , and fast to the clock-work frame, is an insulating-block, R , upon the 25 upper face of which is set the contact-strip r , with its free end lying beyond the block toward the transmitting-wheels, and upon the lower face of said block is affixed the contact-arm r' , whose free end is in contact with the 30 free end of strip r and extends therebeyond and carries the insulating-shoe r^2 upon its end. This shoe r^2 is adjusted to be tripped by cogs T' on wheel T when revolved.

The operation of the clock-work U is under 35 control of the electro-magnets e' and e^2 , each of fifty ohms resistance, and situated below the clock-work. The armature e is supported by lever l , pivoted upon bar k , and carries the hook h , which holds, releases, and catches fly 40 h' , according as the magnets e' and e^2 operate the armature e , thereby controlling the motion of the clock-work. The check-lever l' is also pivoted to bar k to the outside of the clock-work frame, and has its lower short arm secured to the back of armature e , and has its 45 upper end arranged with a stud, l' , which is kept in constant engagement with the periphery and notch W' of the check-disk W by means of the retracting-spring t' , attached between the short arm of check-lever and the 50 clock-work frame. The stud l' normally lies in notch W' , and the spring t' also serves to withhold the armature e from off the magnets. When the armature e is drawn down on the 55 magnets, the stud l' is moved out of notch W' , and hook h releases fly h' , and the clock-work is set in motion and continues to run until the notch W' is again presented to stud l' , which takes into it, while the short arm of check-lever 60 l' raises the armature e from off the magnets, and hook h catches and holds the fly h' , thereby stopping the clock.

The transmitting-wheels V' , V^2 , V^3 , V^4 , V^5 , and T each have five of the circuit breaking 65 and making cogs V and T' , respectively, which are similarly arranged on each wheel to transmit the number-signal 131, while the teeth X

vary on each wheel and are designed to transmit the number of a certain floor of the building in which the signal-box may be located. 70 The transmitting-wheels are shown in normal positions with their respective contact-fingers in contact with the adjacent cogs V and T' , with the exception of finger t , which is normally out of contact with the cog T' contiguous 75 to it, and which is shown in broken lines t' , Fig. 2, as cut away from under the contact-finger t . The insulating-shoe r^2 is below and out of contact with its contiguous cog T' . As the main arbor U' turns and rotates the transmitting-wheels in direction of the arrow in Fig. 2, it is obvious that first the contact-finger t will make contact with the broken cog T' , thus placing all the fingers in contact with their respective wheels, which contact is broken 85 and made and broken again as the wheels are rotated, and the shoe r^2 is tripped by each cog T' sufficiently to cause its arm r' to break and make contact with the free end of strip r . In the same manner will the teeth X on wheels 90 V' V^2 V^3 V^4 V^5 each make and break contact with the respective fingers.

Upon the winding-arbor U^2 of the clock-work is fixed the insulating-collar K , provided with a radial flange which at every complete 95 revolution of said arbor presses and then rests against the tops of two of the three switch-springs O O' O^2 , placed uprightly upon the side of an insulating-block, K , set upon the clock-work frame. This collar is revolved in 100 a direction opposite the hands of a clock, and when it comes to rest against said switch-springs the limit of the motion of the clock-work U is reached, and the winding-arbor is turned backward to again wind up the clock-work. The inner spring, O^2 , is straight, and lies normally in contact with the pin Q^3 on the 105 clock-work frame, and thereby is kept in electric communication with said frame, which, through means of the main arbor U' , is in communication with all the transmitting-wheels mounted thereon. The middle spring, O' , is similar to O^2 , and lies in contact with the connecting-screw K^2 , set in block K' . The outer spring, O , is L-shaped, with its short 110 arm extending across the right-hand face, Fig. 2, of spring O' and out of contact therewith. When the flange on collar K^2 comes to rest against springs O O^2 , the former spring breaks contact with screw K^2 and makes with spring 115 O , and the latter, O^2 , breaks with pin Q^3 .

In the well-known form of the Watkins signal-box a horseshoe electro-magnet is employed, with a ground-wire traversing each arm thereof. I modify this feature of the signal-box by splitting the magnet and traversing magnet e' with a line-wire and magnet e^2 with a ground-wire. The switch J is used to ground box M through post 39, and thereby to transmit the number-signal 131, by means of 120 wheel T and contact-finger t' , in a manner hereinafter described.

The binding-posts 33 35 and 34 32 39 30 31 are disposed at the upper and lower ends of

the base-board of the box, respectively, for joining up the circuits, as hereinafter explained.

In Figs. 1, 6, 7, 8, and 9 my circuit-changer 5 N is illustrated as arranged and used with my improved signal system. The device in itself forms the subject-matter of another application of mine. This circuit-changer N consists of the base-board S, to which is fixed the ordinary clock-work, S', provided with a spring-motor, operating the circuit-changing apparatus connected therewith. The binding-posts s' s² s³ s⁴ s⁵ s⁶ s⁷ s⁸ are arranged near one edge of the base-board, and S² is a casing covering the 15 apparatus.

Upon the main arbor s are the circuit changing wheels C' C² C³ C⁴, which turn therewith, and are provided with the peripheral cogs d' d² d³ d⁴, respectively, which are situated side 20 by side in a line. The trip-disk F is set fast upon arbor s, adjacent to the clock-work frame, and has upon its inner face two studs, F' F². These wheels are insulated from their arbor and are disconnected from each other. The 25 transmitting-wheel P is keyed upon the end of arbor s, which gives an electric communication with frame S², in turn connected by wire at the lower left-hand corner, Fig. 6, to the post s'. The wheel P is provided with the 30 circuit opening and closing peripheral notches P', and upon its outer face has a pin, P², adjusted in alignment with the cogs d' d² d³ d⁴, as shown.

The block Y, of insulating material, located 35 upon the frame below and to one side of arbor s, carries the fixed contact-fingers b' b² b³ b⁴ b⁵ b⁶ b⁷ b⁸ b⁹, the free ends of which lie beneath the transmitting-wheels and out of contact therewith in the following order: Finger b' coacts with the 40 pin P²; finger b² presses upon the periphery of wheel P and breaks contact therewith through the notches P'; fingers b³ b⁴ and b⁵ b⁶ and b⁷ b⁸ and b⁹ lie opposite the wheels C' C² C³ C⁴, respectively, as enumerated. The normal relative 45 positions of these wheels and their fingers are shown in the drawings, and in this condition only one contact-finger, b², is in contact with its coacting wheel. The wheels are controlled, as hereinafter described, to rotate nearly five-sixths of a revolution in the direction of the arrow in Fig. 6, so that when the pin P² and the several cogs d' d² d³ d⁴ come around and press against their respective fingers the wheels 50 will stop rotating, and then all the fingers will be and remain in contact with their coacting parts. During the five-sixths of a revolution the finger b² will have passed over the two series of notches P' upon its wheel, which are 55 arranged to correspond to the break and make 60 cogs on the transmitting-wheels of signal-box M. When the wheels are started again, they will then turn through one-sixth of a revolution and come into their normal positions, as shown. This readjustment is effected by hand. 65 The connecting-screws i' i² i³ i⁴ i⁵ are set down in the block Y so that their lower ends will come in contact with the fingers b⁵ b⁶ b⁷ b⁸ b⁹,

respectively, when said fingers are normal and free from the cogs d' d² d³ d⁴, as shown, and be out of contact therewith when said fingers are 70 raised by said cogs.

The electro-magnets g' g², of seven and seventy ohms resistance, respectively, are mounted in the bracket g³ and g⁴, and are each traversed by the line-wire. The armature g, 75 common to both magnets, is pivoted near its center by the screws g⁵ in the bracket g⁶. The retracting-spring p has one end fixed to the armature g near magnet g² and the other end fixed to the tension-screw p', so that the armature is drawn away from magnet g² and forced 80 down on magnet g'. The trip-lever f is pivoted upon the side of the clock-work frame by the bracket f', and at the lower end has the projection f², bearing upon the end of armature g near magnet g', and is held firmly thereon by means of the spring f³. The upper end of the trip-lever has a wedge shaped extension, f⁴, over the inclined face of which the studs F' F² are pushed by rotation of the disk F. 85 By virtue of this construction when the magnet g² draws down the adjacent end of the armature g the other end thereof slips from under the projection f², which is jammed down between magnet g' and armature g, and this 90 movement causes the hook f⁴, which is fixed upon the back of armature g, to release its confined fly f⁵, thereby starting the clock-work motion and moving the stud F' off the extension f⁶. The motion continues until the stud 95 F² hits upon extension f⁶, depresses that end of lever f, and raises the lower end of said lever, so that the projection is drawn out from the interposition between magnet g' and armature g, whereby the armature g is closed on 100 magnet g' and the hook f⁴ is adjusted to catch and hold fly f⁵ and stop the clock-work.

In Figs. 1, 10, and 11, H designates a thermostat provided with a vibratory and weighted spring-arm. This, however, in itself is not of 105 my invention, but forms the essence of an invention of one Joseph A. Miller. I have merely illustrated this thermostat as connected up in my improved system of signaling. This device consists of the securing-plate A, upon 110 which is set the box A', and both are made of suitable insulating material. The binding-posts a, a', and a² are disposed at opposite ends of the securing-plate, respectively. The binding-screws c' c² are set in opposite sides of the 115 box A' in the same plane, but out of alignment, and are adjustable lengthwise toward or away from each other, and form the electric back and front contacts, respectively, for the thermostat.

The contact-spring c is L-shaped and is set 120 on the inside of the box A', and the free end lies a little below the front contact, c². The metallic plate L is fastened over the open end of box A' and projects to one side thereof in 125 direction of front contact, c². The vibratory curved arm L' is provided with a weight, L³, upon one end, and is passed into box A' through the slot L² in plate L, in which slot it is swiv-

eled on the screws L^5 and vibrates thereon. In normal condition the weight L^3 is held, as shown, by the clip L^6 , which is made fast to the metallic plate L and the weight L^3 by the easily-fused solder L^4 , while the other end of arm L' presses against back contact, c' . When the heat fuses the solder and allows the weight to fall, the arm leaves back contact, c' , and strikes upon contact-spring c , and then upon front contact, c^2 , and the vibrations of the said arm will make and break with contacts c^2 a series of times, and finally comes to rest against front contact, c^2 , and spring c . The vibratory arm L' is in electrical communication with plate L , which is in turn connected to post a' of wire 50. The contacts c' and c^2 and post a' are electrically connected by wires 51 and 52, and contact-spring c is connected by wire 53 with post a^2 . In operative position the thermostat is secured by plate A in position of Fig. 11.

In Figs. 1, 12, and 13, Z designates an ordinary form of switch-board for electric circuits as used with my system. This board has disposed at one end four binding-posts, 60 62 and 61 63, in pairs, for the in and out going lines, respectively, of the system.

The switch-arms 64, 65, and 70 swing on their pivoted ends and are adjustable upon the contact-buttons 66 67 68 and 69 71, respectively, which are electrically connected in an evident manner, as shown in the drawings. The holes 72, 73, and 76 are break-holes, which are filled or bridged by the switch-plug 77, shown in its resting hole, being transferred to the desired hole and there inserted. The binding-posts 74 and 75 are arranged at one end of the board Z and form the ground-connections for ground Z' adjacent thereto. The switch-board Z is shown in normal condition, and obviously if the switch-plug be placed in hole 76 the ingoing and outgoing lines above alluded to will be short-circuited.

The thermostat H has its front and back contacts in the same circuit, and also has a ground-contact, c . I therefore term the device a "thermostatic switch," having three ways or contacts.

My fire-alarm system is operated on a complete metallic circuit normally closed and furnished with electric current from office battery 20, the poles of which are connected with switches 22 and 23, respectively, of switch-board 21, having adjacent ground 25, and from the poles over said switches run the negative and positive lines, respectively. The relay-magnets 26 and 27 are situated in the metallic circuit, one near each pole of battery 20, and normally have their armatures closed.

The fire-battery 50, also at the central station, has a ground, 55, a relay-magnet, 54, and a switch-board, 51, provided with contact 53 and switch-arm 52, whereby said battery may have its power put on either the positive or negative side of the metallic circuit and reinforce battery 20, or battery 50 may be cut out. The fire-battery 50 and its relay and

switch are on the normally-open ground-circuit hereinafter described. The batteries, their relays, switches, and grounds, just described, are all located at the central station. The mechanisms consisting of the switch-board Z , circuit-changer N , signal-box M , and thermostat H are situated at a local point or building distant from the central. 75

The diagrammatic plan view of the system shown in Fig. 1 represents the system under normal condition.

The complete metallic circuit is normally closed, and leads by the positive pole from battery 20, through switch-arm 23, relay-magnet 26, over switch-board Z , to post s^5 of circuit-changer N ; thence it passes to connecting-screw i^9 , to contact-finger b^9 , post s^6 , thence to split 90 in wire at a point below signal-box M , 85 Fig. 1, then back to circuit-changer and to post s^2 , forming the first branch-point, from where it branches, and one branch leads as follows:

From post s^2 it passes over the retaining-magnet g' , which has armature g held thereon by spring-pressure, as before described; thence it passes to connecting-screw i^8 , over contact-finger b^8 , by wire to contact-finger b^5 , to connecting-screw i^5 , post s^4 , to post a in thermostat H , thence to contact c' , arm L' , plate L , to post a' , and back to circuit-changer, to post s^3 , thence to contact-finger b^7 , connecting-screw i^7 to post s' , which forms the second branch-point of the branches, from where it goes by the negative line to switch-board Z , relay 27, 100 switch 22, to battery 20. The other branch leads from the first branch-point at post s^2 of circuit-changer over the actuating-magnet g^2 , contact-finger b^2 , over wheel P , thence by arbor over clock-work frame to the second branch-point post s' , thence to line and to battery 20, as described. Considering this normally-closed metallic circuit, when the thermostatic switch H is made to vibrate between the contacts c' and the contacts c and c^2 at the 110 times when the arm L' is out of contact with all of said contacts, the current will be off of the retaining-magnet g' and on the actuating-magnet g^2 , so that a series of vibratory motions of the switch will serve to send 115 a sufficient number of impulses over actuating-magnet g^2 to cause it to attract its armature g and start the circuit-changer. When the vibration of the thermostats ceases, the normally-open metallic circuit will be re-established as follows: The cogs on the circuit-changing wheels and the pin P^2 on the transmitting-wheel having come to rest against the several contact-fingers b^1 b^2 b^3 b^4 b^5 b^6 b^7 b^8 b^9 and broken their connection with connecting-screws i^5 i^6 i^7 i^8 i^9 , as fully described hereinbefore, the re-established metallic circuit leads over the negative line to post s' in circuit-changer N , over frame and arbor to transmitting-wheel P , pin P^2 , contact-finger b^7 , post s^2 , to post 32 in signal-box M , to springs r and r' , to post 31, thence to post s^3 in circuit-changer, to contact-finger b^6 , cog d^2 on wheel c^2 , to contact-finger b^5 , by wire to b^8 , to cog d^3 , contact-

120 125 130 135

finger b' to post s^3 to thermostat H, and there-through in an obvious path to post s^4 in circuit-changer, contact-finger b^4 , cog d' , to contact-finger b^5 , to post s^7 , thence to post 30 in signal-box M, over controlling-magnet e' to post 33, and over the positive line to battery 20. In this re established metallic circuit the contact-springs r and r' , provided with the shoe r^2 , when tripped by cogs T' on wheel T, as before explained, will record their makes and breaks of their circuit on relays 26 and 27 when the circuit-changer has operated and the signal-box runs.

It will also be seen that in normal condition, 15 if the metallic circuit be broken on the branch containing the retaining-magnet g' , the circuit-changer will be started by the actuating-magnet g^2 receiving the full current from battery 20, and in operating the transmitting-wheel P, with its coacting finger b^2 , will transmit the number 131 per notches P' twice, which will be recorded on relays 26 and 27.

The normally-open ground-circuit leads from the ground-connection of the metallic closed circuit at central orifice over fire-battery 50, relay 54, by both the negative and positive lines of the normally-closed metallic circuit to arm L', and terminates at contact c^2 in thermostat H. From the terminal c in thermostat it passes to post 35 in signal-box M, over contact-finger v' , wheel V', arbor and clock-work frame to stud O', spring-switch O', thence to controlling-magnet e^2 , to post 34, to switch-board Z, and to ground Z'. When the office-ground 55 finds ground Z' by either the negative or positive line of the normally-closed metallic circuit, this normally-open ground-circuit will be closed, and the controlling-magnet e^2 being energized, the signal-box 25 M will be started, and since said ground-circuit is preserved at one point over contact-finger v' and transmitting-wheel V', the circuit openings and closings thereby over either intact line of the metallic circuit will be recorded on the responsive relay-magnet 54. The wheel V' thus serves to record at the central station the number 131 per its cogs V for the building in which the apparatus is located and 8 per its teeth X for the floor of the building 30 on which the operating-thermostat is located. The openings and closings of the re-established metallic circuit over the contact-springs r and r' merely record the confirmatory signal-number 131 on relays 26 and 27, according to the teeth T' on wheel T. When 35 the predetermined degree of temperature operates the thermostat H, as described, the continuity of the normally-closed metallic circuit is destroyed by the vibratory motion of the thermostat, which then serves to energize the actuating-magnet g^2 , located in the other branch from the thermostat, and thus start the circuit-changer. In the meantime, the contact c having been made a sufficient number 40 of times, the central ground, 55, finds local ground Z', and so energizes controlling-magnet e^2 of the signal-box and starts the same,

which records its signal-number on relay 54, as before described. The intermittent current which is sent over magnet g^2 sufficiently 70 to energize the same and start the circuit-changer is not sufficiently continuous to allow the transmitting-wheel P and contact-finger b^2 to record the openings and closings per notches P'. When the circuit-changer comes to rest 75 at five-sixths of a revolution, the re established metallic circuit made through said circuit-changer will have its contact-springs r and r' record on relays 26 and 27 the signal-number 131, which thereby gives a signal confirmatory 80 to the signal recorded in relay 54 by signal-box M.

The thermostatic switch H, I construct to give between twenty and twenty-five vibrations, or any necessary number, which insures 85 the passing of the intermittent current over actuating-magnet g^2 sufficiently to energize the same.

The signal-box M may be grounded by hand on the normally-open adjacent ground Z' by 90 switching the arm J from left to right, Fig. 1, thereby connecting arm Z' with arm J', which will give ground Z' to the central ground, 55, over both the positive and negative lines of the normally-closed and intact metallic circuit, to the split point 90 in said circuit, whence it passes to post 39, and over the connected arms Z' and J', by wire to contact-finger t' , over cogs T' on wheel T, thence over the clock-frame to spring O', traversing and energizing 100 magnet e^2 , to post 34, thence to binding-posts 75 and 74, and to ground Z', thereby starting box M and recording the number-signal 131 on relay 54, according to the circuit openings and closings by finger t' and the cogs T', of 105 uniform size. The normal condition of the working-circuit is not disturbed by this grounding by hand of box M to give a fire-alarm designating the building only.

The portion of the initial cog T' lying directly under contact-finger t is cut away so as to leave a very narrow piece to make and break with finger t . This is for the purpose of gaining a peculiar danger or trouble signal on relay 54 in case the box M is accidentally 115 set off—by being jarred, for instance. In this case of accidental starting the signal 131 will be recorded on relay 54 by the central ground, 55, finding ground Z' over both the positive and negative lines of the normally-closed metallic circuit, to split post 90, thence to post 32, over spring O' to contact-finger t , cogs T' on wheel T, over frame of the clock-work and over spring O', over magnet e^2 , which it energizes, thence by post 34 to ground Z' in board 120 Z. The initial cog T', which the coacting contact-finger t makes and breaks with, is cut away, as described, and the first number recorded will be very brief and will thereby be recognized as an accidental alarm.

I have shown the use of a single thermostatic switch H in the system, which represents the eighth floor of a building. Of course the number of switches H may be increased

as desired. For instance, three more may be cut in on the branch with the one shown and connected up with signal-box M by posts 80, 81, 82, and 83 in an obvious manner with con- 5 tact-fingers v^2 v^3 v^4 , respectively.

The operations of my fire-alarm system will now be considered with reference to defective conditions of grounds and breaks in the several parts thereof which are likely to occur.

10 In case of a break on the branch of the normally-closed metallic circuit containing the retaining-magnet g' , the occurrence of said break is made known at the central station by the current passing over the branch contain- 15 ing the actuating-magnet g^2 , thereby starting circuit-changer and recording over both positive and negative lines upon relays 26 and 27 the number-signals 131 131, as per notches in the transmitting-wheel P, opening and closing 20 said circuit by its coacting finger b^2 , as before described. Under this condition of the circuit-changer having operated to re-establish the circuit a fire-alarm may be received on relay 54 by virtue of the normally-open ground- 25 circuit being established over the intact line of the re-established metallic circuit, as before described for said open circuit. Considering that this break occurs in a building during the night when not accessible, the switch- 30 board Z being located to the outside of said building, an operator goes to the building, according to the signal of defect having been announced by the circuit-changer, and manipulates the switch-board by removing switch- 35 plug 77 from its resting-hole and inserts it in break-hole 76, thereby short-circuiting the normally-closed metallic circuit from said local point and restoring to normal condition the system for the other connected buildings 40 in line therewith. It is obvious that this short-circuiting does not defeat the signal-box M from subsequently sending a fire-alarm over the open ground-circuit, as described, for the connections of the switch-board Z afford 45 uninterrupted path therefor, as in the normal condition.

In the case of a break on the normally-closed metallic circuit outside of the branch just described, the same is denoted by the armatures 50 of relays 26 and 27 falling away from their magnets and remaining so until the continuity of the circuit is restored by hand. Under this condition a fire-alarm may be received on relay 54 from signal-box M over the intact 55 line of the normally-closed metallic circuit, as described for the normally-open ground-circuit, since the circuit-changer and thermostatic switch remain unaffected.

In the case of a ground on the normally-closed 60 metallic circuit or any part of the normally- open ground-circuit destroyed, the fire-battery 50 is switched off by switch-arm 52 in order to destroy the effect of the defective ground on said normally-closed metallic circuit, and the 65 system is then worked on said latter circuit, over which a fire-alarm may be recorded on relays 26 and 27 by the circuit openings and

closings of the contact-springs r and r' being tripped, as by the description hereinbefore given.

70

In the case of a short circuit on the normally-closed metallic circuit the thermostatic switch, circuit-changer, and signal-box act as described in case of no defect, and a fire-alarm may be recorded on relay 54 from signal-box 75 M by the normally-open ground-circuit by three paths—viz., over each of the lines of the normally-closed metallic circuit and by the short circuit itself to the thermostatic switch.

In the case of the normally-closed metallic 80 circuit having one line open and the other grounded, considering the condition of the positive line grounded and the negative open, switch-arm 22 of board 21 is moved onto ground 25, thereby establishing the positive 85 and negative lines as closed and open, respectively. Considering the condition reversed—that is, negative line grounded and the positive open—switch-arm 23 is grounded on ground 25 and switch-arm 52 is moved onto 90 point 53, thereby making the negative and positive lines open and closed circuits, respectively. Under these conditions the alarm may be received on the open circuits according to the cases described for the closed and open 95 circuits, respectively. Under the conditions of a break on the normally-closed metallic circuit outside of a building and both ends grounded at said break, a fire-alarm may be received by opening switch-arm 52, so as to break ground 55, and working on the closed metallic circuit, as before described, and the re-established metallic circuit over springs r and r' will record the fire-alarm.

100

Having thus described my invention, I claim 105 as new and desire to secure by Letters Patent—

1. In a fire-alarm system, in combination, a normally-closed metallic circuit having branches therein and an included relay and a circuit-changer, substantially as described, having in one branch its retaining-magnet and in the other branch its actuating-magnet and transmitting device, whereby a signal may be recorded on said relay, substantially as de- 115 scribed.

2. In a fire-alarm system, in combination, a normally-closed metallic circuit having branches therein and an included relay, an open metallic circuit and a signal-box included therein, and a circuit-changer, substantially 120 as described, situated in both of said circuits and having in one branch its retaining-magnet and in the other branch its transmitting-device and actuating-magnet, whereby said circuit-changer may automatically record a sig- 125 nal upon said relay and close said open metallic circuit, substantially as described.

3. In a fire-alarm system, in combination, a normally-closed metallic circuit having branches therein and an included relay, a nor- 130 mally-open metallic circuit and an included signal-box provided with a tripping device, and a circuit-changer, substantially as described, situated in both of said circuits and having in

one branch its retaining-magnet and in the other branch its transmitting device and actuating-magnet, whereby said circuit-changer may automatically act in succession to record 5 a signal and close the open metallic circuit and the tripping device may act to record a fire-alarm upon said relay, substantially as described.

4. In a fire-alarm system, in combination, 10 a normally-closed metallic circuit having branches therein and provided with a normally-closed ground-connection having a relay at the central station, a normally-open metallic circuit, a circuit-changer, substantially as described, situated in both of said metallic circuits and having its retaining and actuating magnets located respectively in said branches, and a signal-box included in said open metallic circuit, said box having an open 20 ground-connection and a controlling hand-switch therefor, whereby said box may be grounded to record a fire-alarm upon said relay, substantially as described.

5. In a fire-alarm system, in combination, 25 a normally-closed metallic circuit having branches therein and provided at the central station with a normally-closed ground-connection having a relay therein, a three-way thermostatic switch situated in one of said 30 branches, a circuit-changer, substantially as described, having its retaining-magnet in the branch with the thermostatic switch and its actuating-magnet in the other branch, and a signal-box provided with an open ground-connection controlled by said switch, whereby 35 said box may record a fire-alarm upon said relay.

6. In a fire-alarm system, in combination, 40 a normally-closed metallic circuit having branches therein and included relays and a normally-closed ground-connection also provided with a relay at the central station, a normally-open metallic circuit, a three-way thermostatic switch adapted to make a series 45 of contacts and located in one of said branches, a circuit-changer, substantially as described, having its retaining-magnet in said branch with said switch and its actuating-magnet in the other said branch, and a signal-box located 50 in said open metallic circuit and provided with a tripping device, and having an open ground-connection controlled by said switch, whereby said box may record a fire-alarm upon the relay in said closed ground-connection, and the 55 circuit-changer close the open metallic circuit, and the tripping device record an alarm upon the relays on said closed metallic circuit, substantially as described.

7. In a fire-alarm system, in combination, 60 a normally-closed metallic circuit having a relay and a grounding-switch in the positive and negative lines each and provided at the central station with a normally-closed ground-connection having a relay and a switch controlling both said positive and negative lines, a normally-open metallic circuit, a three-way thermostatic switch adapted to make a series

of contacts and included in a branch of said closed metallic circuit, a circuit-changer, substantially as described, having its retaining-magnet in the branch with said thermostatic switch and its actuating-magnet in a branch around said thermostatic switch, and a signal-box, substantially as described, located in said open metallic circuit and provided with an open ground-connection controlled by said thermostatic switch and by hand, substantially as described. 70

8. In a fire-alarm system, in combination, a normally-closed metallic circuit having at the 80 central station a relay and grounding-switch in its positive and negative lines each and provided at the central station with a normally-closed ground-connection having a relay therein and a switch controlling both of said 85 lines, and a local point in said closed metallic circuit containing the following elements, viz: an open metallic circuit, a three-way thermostatic switch adapted to make a series of contacts and located in a branch of closed 90 metallic circuit, a circuit-changer included in said metallic circuits, substantially as described, a signal-box, constructed substantially as described, having an open ground-connection controlled by said thermostatic switch and 95 by hand, and a short-circuiting device including both said positive and negative lines, whereby said circuit may be short-circuited from the local point, substantially as described. 100

9. A fire-alarm system consisting of a closed metallic circuit provided at the central station with relays and a closed ground-connection, also having a relay, and a series of local points located in said closed metallic circuit, each containing the following elements, viz: an open metallic circuit, a thermostatic switch adapted to make a series of circuit openings and closings and located in a branch of said closed metallic circuit, a circuit-changer included in 105 said open and closed metallic circuits, substantially as described, and having its retaining-magnet in the branch with said thermostatic switch and its actuating-magnet in a branch around said thermostatic switch, a signal-box provided with a tripping device and included in said open metallic circuit and having an open ground-connection controlled by 110 said thermostatic switch, and a short-circuiting device included in said closed metallic circuit, whereby said circuit may be short-circuited, 115 substantially as described. 120

10. A fire-alarm system consisting of a closed metallic circuit having at the central station a relay and a grounding-switch in the 125 positive and negative lines each, and also having at the central station a normally-closed ground-connection provided with a relay and a switch controlling said lines, and a series of local points located in said closed metallic circuit, containing the following elements, viz: an open metallic circuit, a three-way thermostatic switch adapted to make a series of contacts and included in a branch of said closed metal- 130

lic circuit, a circuit-changer included in said open and closed metallic circuits, substantially as described, a signal-box provided with a tripping device and having an open ground-
5 connection controlled by said thermostatic switch and by hand, and a short-circuiting device included in said closed metallic circuit, whereby said circuit may be short-circuited from a local point, substantially as described.
10 11. In a fire-alarm system, a normally-closed metallic circuit normally grounded at the central station, a three-way thermostatic switch

at a point in said circuit, and a ground adjacent thereto, said switch adapted to make a series of short contacts, thereby opening and closing said closed metallic circuit and closing and opening said adjacent ground, or operating reversely.

In witness whereof I have hereunto set my hand.

CHARLES BURGHIER.
